UNITED STATES PATENT OFFICE.

JOHN WALKER GAY, OF SODAVILLE, OREGON.

BED FOR RAILWAY-TRACKS.

SPECIFICATION forming part of Letters Patent No. 664,740, dated December 25, 1900.

Application filed May 22, 1900. Serial No. 17,599. (No model.)

To all whom it may concern:

Be it known that I, JOHN WALKER GAY, a citizen of the United States, residing at Soda-ville, in the county of Linn and State of Oregon, have invented a new and useful Bed for Railway-Tracks, of which the following is a specification.

This invention relates to railway-tracks, and has for one object to provide an improved bed therefor, so as to hold the rails firmly in place and to prevent them from spreading by the weight of a train. It is furthermore designed to provide improved means for connecting the opposite track-sections and to connect the abutting rail-sections.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a top plan view of a section of a railway-track constructed in accordance with the present invention. Fig. 2 is a side elevation thereof. Fig. 3 is a transverse sectional view taken on the line 3-3 of Fig. 2. Fig. 4 is a detail view of one of the fish-plates.

Corresponding parts in the figures of the drawings are designated by like characters of reference.

Referring to the accompanying drawings, 1 and 2 designate the opposite rails of the track, which are supported upon the longitudinal stringers 3, which are considerably wider than the respective rails, so as to form a substantial base or bed therefor. At suitable intervals throughout the length of the stringers transverse sockets or recesses 4 are formed entirely across the upper face of the stringers for the reception of a rail-chair 5, which is provided with an intermediate transverse groove 6 in its upper face, and to form a seat for the base-flange of the rail, as best shown in Fig. 3 of the drawings. As indicated in Fig. 2, the upper face of the rail-chair extends above the upper face of the stringer

and is flush with the upper face of the flange of the rail. In each inner and outer edge of the stringer there is provided a vertical 55 groove or recess 7, which intersects the contiguous end of the adjacent transverse recess 4 and is designed for the reception of an angled track-fastening plate 8, which fits flush with the outer face of the stringer and overlaps both the adjacent end portion of the rail-chair and the flange of the rail. This angled plate is secured in place by means of screw-threaded fastenings 9, which pass transversely into the stringer, and by similar fastenings 10, which pass downwardly through the upper portion of the plate, the rail-chair, and into the stringer, thereby securing both the rail-chair and the rail firmly to the stringer.

As indicated by dotted lines in Figs. 1 and 2, the abutting ends of the stringers are preferably arranged at the rail-joints, and a comparatively wide fastening-plate is employed to secure a rigid connection between the 75 stringers and the rails. Also opposite arched fish-plates 11 and 12 are placed against the respective sides of the webs of the rails, so as to overlap the joint therebetween, and are held in place by means of suitable bolts 13. 80 These fish-plates are arched, so as to accommodate the upper portion of the angled fastening-plates and to fit down firmly upon the flanges of the rails and at opposite sides of the fastening-plates. The opposite stringers 85 are braced and connected by means of a plurality of tie-bars 14, which extend in opposite directions through the stringers and the respective transversely-aligned angle-plates and provided at their outer projecting ends with 90 nuts 15, which are set against the outer faces of the angle-plates to hold the rods in place, and thereby prevent separation of the stringers and the opposite rails of the track. Each tie-bar is provided with a pair of transverse 95 pins or keys 16, which project radially at opposite sides of the bar and are spaced at equal predetermined points, so as to bear against the inner sides of the respective stringers and form guides or gages to properly space 100 the stringers and preserve the standard gage of the track. Instead of pins lugs may be employed to form stop-shoulders for the same purpose.

From the foregoing description it will be apparent that the rails are firmly secured to the stringers and that the latter are effectively braced and connected, so as to prevent separation of the rails by the weight of a train. Also as the stringers and the rails are connected to form a practically continuous track little or no ballast is required to form a solid and substantial road-bed, although ballast may be employed without affecting the structure in any manner whatsoever.

What is claimed is—

1. In a railway-track, a stringer, having a transverse socket or recess formed in the upper face thereof, a rail-chair seated in the socket or recess, a rail supported upon the chair, and opposite angle-plates embracing opposite sides of the stringer, overlapping the adjacent end portions of the rail-chair and the flanges of the rail, and also secured to the stringer.

2. In a railway-track, a stringer, having a transverse socket or recess formed entirely across the upper face thereof, and also vertical recesses intersecting the opposite ends of the transverse sockets, a rail-chair seated in the transverse socket, and having a transverse groove or seat, a rail having its flange received within the seat of the chair, opposite angle-plates fitted in the respective vertical recesses and overlapping the adjacent end portions of the rail-chair and the flanges of the rail, and fastenings, some of which pass

transversely through the angle-plates and the stringer, and others pass downwardly through the upper portions of the plate, the rail-chair and into the stringer.

3. In a railway-track, the combination of opposite stringers, having corresponding transverse sockets in the upper faces thereof, and vertical recesses in the outer and inner faces and intersecting the opposite ends of the transverse sockets, rail-chairs seated in the respective sockets, and provided with transverse grooves, rails having their flanges seated in the respective grooves of the chairs, opposite angle-plates fitted in the respective vertical recesses and overlapping the respective end portions of the rail-chairs and the flanges of the rails, arched fish-plates fitting the webs of the rails and embracing the upper portions of the angle-plates, fastenings for the fish-plates, and transverse tie-bars extending in opposite directions through the stringers and corresponding angle-plates, nuts provided upon the outer projecting ends of the bars, and intermediate spaced gage-shoulders carried by the bars and for engagement with the inner faces of the respective stringers.

In testimony that I claim the foregoing as my own I have hereto affixed my signature in the presence of two witnesses.

JOHN WALKER GAY.
